F. L. MYERS,
TELEPHONE SWITCH,
APPLICATION FILED JAN. 29, 1915.

1,152,336.

Patented Aug. 31, 1915.

UNITED STATES PATENT OFFICE.

FRED L. MYERS, OF DEWITT, IOWA, ASSIGNOR OF ONE-HALF TO THOMAS FOLEY, OF CHARLOTTE, IOWA.

TELEPHONE-SWITCH.

1,152,336.

Specification of Letters Patent. Patented Aug. 31, 1915.

Application filed January 29, 1915. Serial No. 5,146.

To all whom it may concern:

Be it known that I, FRED L. MYERS, a citizen of the United States, residing at De-witt, in the county of Clinton and State of Iowa, have invented new and useful Improvements in Telephone-Switches, of which the following is a specification.

This invention relates to a telephone switch, and the primary object of the same is to provide automatically operating means for cutting out or relieving talking subscribers on party lines from annoyance and inconvenience in conversation by the various noises in homes of subscribers other than those talking and due to interference of non-talking subscribers who remove the receivers from the supporting switch arms of their telephones and place the latter in the talking circuit to ascertain the nature of the conversation of the talking subscribers, various noises in the houses or rooms of non-talking subscribers being usually transmitted to the talking subscribers by each curious or eavesdropping non-talking subscriber cutting into the line.

The invention in the present instance consists of an improvement on the construction and arrangement of parts disclosed by my pending application Serial No. 863,679, filed September 26, 1914, and which will be more fully hereinafter described and claimed.

In the drawing: Figure 1 is a sectional perspective view of a switch embodying the features of the invention. Fig. 2 is a longitudinal vertical section of a portion of a casing showing the improved switch in one of its adjusted positions. Fig. 3 is a view similar to Fig. 2 illustrating another position of the parts of the switch. Fig. 4 is a detail top plan view of a portion of the switch organization.

The numeral 5 designates a part of the casing or framework of an ordinary subscriber's telephone equipment having a switch lever 6 suitably forked to hold a receiver 7, as shown in dotted lines in Fig. 1. The lever 6 is fulcrumed to a support 8, as at 9, and movably projects through a slot 10 in the one end of the casing or framework 5, and around this slot and on the outer side of the end of the casing or framework an escutcheon plate 11 is secured which is vertically slotted, as at 12, the said slot 12 in the present instance being of uniform width throughout its vertical extent. The

slot 12 of the escutcheon extends fully through the lower end of the latter, as at 13, to facilitate the application of the said escutcheon over the exteriorly projecting portion of the switch lever 6. The upper end wall 14 of the slot 12 is located slightly below the upper terminating wall of the slot 10 in the end of the casing so that when the lever 6 moves upwardly its full vertical extent as determined by prearrangement, the upper edge of the said lever will strike the upper end wall 14 of the slot 12 instead of engaging the upper end wall of the slot 10, and by this means wear of the upper end wall of the slot 10 will be prevented.

The lever 6 bears on the upper free end of an elongated looped spring 15 which has its lower end attached to an insulating base 16 secured to the bottom of the casing 5. The upper free end of the spring 15 engages the under edge of the lever 6 adjacent to the fulcrum support 8 of the said lever, and depending from the fulcrum of the lever and extending outwardly below the latter is an arm 17 having an angularly projecting pin 18 at its free end. The pin 18 loosely engages the free bent or hooked end 19 of a spring contact leaf or member 20 having shorter spring contact leaves or members 21 and 22 arranged in superposed relation thereto and to each other. The leaves or members 20, 21 and 22 are all held on the insulating base 16, and interposed between them and the base are insulating space strips 23, one of said insulating strips 23 being arranged on the top surface of the leaf or member 22 for engagement by the heads of the fastening screws or other devices 24 for all of said leaves or members. The leaves or members 20 and 21 are also respectively provided with contact points 25 and 26, and all the leaves or members have their inner ends 27, 28 and 29 reduced and preferably bent upwardly for conveniently attaching wires 30, 31 and 32 for connecting the leaf or member 20 to the line, the leaf or member 21 to the receiver, and the leaf or member 22 to the transmitter.

The improved features of the present invention consist of a partially automatically operating means for controlling the vertical movement of the switch lever 6, and the said means embodies a catch 33 pivoted at its upper end, as at 34, to the escutcheon plate 11 and adjacent end of the casing 5.

The escutcheon plate 11 is formed with an angularly bent outwardly projecting guide flange 35 which is formed with a vertical slot 36 and in the said slot a push lever or bar 37 is mounted and has a front head 38. The rear end of the push lever or bar 37 is movably connected to a pin 39 projecting outwardly from the catch 33 below its fulcrum 34. The catch 33 is cut away or recessed as at 40, to provide a clearance for the lever 6 and also a projection or nose 41 which is adapted to engage the flange 35 at a point close to the escutcheon plate 11. By recessing the catch 33 the latter is given such contour as to provide a depending lever engaging member 42 having a lower squared end 43 against which the upper edge of the lever is adapted to contact. Normally the lower squared end 43 of the lever engaging member 42 is disposed over the lever 6 and partially closes the slot 12 of the plate 11, and to maintain the said lever engaging member 42 in the normal position just described a spring 44 is attached to the pin 33 and to a projection 45 preferably cut and bent rearwardly from the flange 35, as clearly shown by Fig. 4. The spring 44 is strong enough to draw the lever engaging member 42 forwardly when the switch lever 6 is depressed below the plane of the lower squared end 43 of the said member, and the catch will automatically operate when the switch lever 6 is depressed to move forwardly over the upper edge of the switch lever and across or over the upper portion of the slot 12 of the escutcheon plate 11. The lever engaging member 42 of the catch is released from the switch lever 6 by pressing rearwardly on the head 38 and release lever or bar 37, such movement of the release lever or bar 37 operating to swing the catch 33 as a whole on its fulcrum 34 against the resistance of the spring 44, and when the lower squared end 43 of the lever engaging member 42 clears the upper edge of the switch lever 36 the latter is permitted to rise or move upwardly the full extent or predetermined distance in the slot 12 by reason of the formation of the recess 40 in the catch. When the switch lever 6 is depressed to clear the lower squared end 43 of the lever engaging member 42, the spring 44 immediately comes into action and the catch 33 is drawn forwardly until the projection or nose 41 strikes the flange 35 and at which time the lever engaging member 42 will be in normal position over the upper portion of the slot 12 of the escutcheon plate 11. In manipulating the catch attachment as just explained only a slight pressure is required on the head 38 to effect a release of the switch lever 6. The lower or squared end 43 of the lever engaging member 42 is elevated some distance above the lower terminating wall of the slot 10 in the end of

the casing so that the switch lever 6 will be permitted to have a slight upward movement when the receiver is released from the fork, but the upward movement of the switch lever 6 will be limited by the same coming in contact with the lower squared end 43 of the said member 42.

When the receiver is on the outer forked end of the lever 6 the latter is held down close to the lower terminating wall of the slot 10 and some distance below the lower squared end 43 of the lever engaging member 42, and in this condition the telephone instrument as a whole will be ready for signaling. When the lever 6 is in signaling position, as shown by Fig. 1, all the leaves or members 20, 21 and 22 are out of contact, or the talking circuit is open. When the receiver 7 is removed from the lever 6 by a subscriber the said lever automatically springs or moves upwardly through the action of the spring 15 thereon and strikes the lower squared end 43 of the lever engaging member 42, as shown by Fig. 2, and the spring leaf or member 20 is drawn upwardly by the action of the arm 17 and the contact point 25 engages the lower side of the leaf or member 21 and thereby connects the receiver in the line circuit, the leaf or member 22, however, being free of contact with the leaf or member 21 below, and hence the transmitter is not connected in the line circuit. When the lever 6 is released by pressing on the head 38 and forcing the lever 37 backwardly to rearwardly swing the catch 33 as a whole on its fulcrum 34 and release the lower end 43 of the lever engaging member 42 from the lever 6, the said lever 6 is permitted to move upwardly to its full predetermined extent in the slots 10 and 12 respectively in the end of the casing and the escutcheon plate 11, the lever 6 being thus forced upwardly by the spring 15 until it strikes the upper end wall of the slot 12, and when the switch lever is in this full elevated position the leaf or member 20 will be drawn up a greater distance and therewith the leaf or member 21 to set up a complete engagement of the contact points 25 and 26 respectively with the leaves or members 21 and 22, as shown by Fig. 3, the receiver and transmitter under the latter conditions being both connected in the line.

When the leaves or members 20, 21 and 22 are in the position shown by Fig. 2 with the switch lever 6 bearing against the lower end 43 of the lever engaging member 42 of the catch, the transmitters of the instruments in the homes or rooms of subscribers taking down their receivers to listen to the conversation of subscribers regularly connected up will not be connected in the line, and hence the noises in such homes or rooms of the listeners or eavesdroppers will not be heard

- by the regularly connected subscribers, though other subscribers on the line may hear the conversation of the regularly connected and conversing subscribers.
5. The advantage of the improved attachment is the ability of the conversing subscribers to readily and locally control their instruments so that conversation will be clear and uninterrupted by noises transmitted through the instruments of other subscribers included in the line, and the conversing subscribers will have also freedom of conversation.

10 Another advantage in the improvement is that when the lever 6 is held against the lower end 43 of the lever engaging member 42 the batteries in the various local telephone equipments are not in use or are cut out, thereby providing a material saving in 15 battery strength as well as avoiding the noises incident to connection of all the batteries with the line.

20 Various kinds and forms of boxes, casings or frames are used in local telephone equipments, and the improved switch is adapted for application to any and all of the forms 25 of boxes or casings now in use. Moreover, the leaves or members 20, 21 and 22 and the arm 17 together with the insulating devices 30 or strips 23 may be readily applied to switch levers now in use with comparatively little trouble, and likewise the catch attachment 35 may also be easily disposed in operative position in connection with the present form of switch levers.

What is claimed is:

1. The combination with a telephone switch lever, of means for giving a variable movement thereof, consisting of a manually 40 controlled catch having an automatic return movement to normal position when released, and yielding contact members movable by the switch lever and adapted to be respectively connected to line, the receiver and the 45 transmitter of a local telephone equipment, the variable movements of the lever setting

up an engagement of either two or all of the said contact members.

2. The combination with a telephone switch lever having variable vertical movements, a manually controlled catch device movably mounted over the switch lever and having an engaging member for the lever to check the upward movement of such switch lever, the catch being automatically 55 returned to normal position over the lever when released, and yielding contact members movable by the switch lever and adapted to be respectively connected to line, the receiver and the transmitter of a local telephone 60 equipment, two of the contact members being brought into engagement when the lever is held against full vertical movement thereof.

3. The combination with a telephone 65 switch lever having vertical movement when released, of a catch having a depending switch lever engaging member and fulcrumed at its upper extremity, the catch being provided with spring means for returning it to normal position and also with an operating lever for releasing the said member from the switch lever, and three insulated yielding contact members movable by the switch lever and adapted to be respectively connected to line, the receiver and the transmitter of a local telephone equipment, the switch lever when checked in its vertical movement causing engagement of contact members adapted to be connected to the line 70 and the receiver, and the full vertical movement of the switch lever effecting engagement of all the contact members and connecting the receiver and the transmitter to the line.

In testimony whereof I have hereunto set my hand in presence of two subscribing witnesses.

FRED L. MYERS.
